2 SHEETS—SHEET 2.

UNITED STATES PATENT OFFICE.

GEORGE L. REUSCHLINE, OF PHILADELPHIA, PENNSYLVANIA.

APPARATUS FOR MAKING CAN-ICE.

1,360,315.

Specification of Letters Patent. Patented Nov. 30, 1920.

Application filed March 7, 1918. Serial No 220,942.

To all whom it may concern:

Be it known that I, GEORGE L. REUSCHLINE, a citizen of the United States, residing in the city and county of Philadelphia, State 5 of Pennsylvania, have invented certain new and useful Apparatus for Making Can-Ice, of which the following is a specification.

My invention relates to ice making apparatus, and more particularly such as may be 10 employed for making can ice.

My invention resides in apparatus of the character referred to comprising a traveling carriage or crane movable with respect to a freezing tank in which the cans are 15 disposed, and carrying a tank or reservoir, preferably divided into compartments, containing the water to be frozen and delivered into the cans from the tank or reservoir.

My invention resides also in apparatus for 20 hoisting a can containing ice from a freezing tank, transferring it to a thawing or dip tank, and for thereafter placing the can upon a dump board and tilting the board with the can thereon to position for 25 moving the ice from the can.

My invention resides also in a hook structure whereby a can may be hoisted and transported.

My invention resides in apparatus of the 30 character hereinafter described and claimed.

For an illustration of one of the various forms my invention may take, reference is to be had in the accompanying drawing, in which:

35 Figure 1 is a side elevational view, some parts in vertical section, of apparatus embodying my invention.

Fig. 2 is an elevational view of the left end of the apparatus shown in Fig. 1, 40 partly in section.

Fig. 3 is an elevational view of part of the apparatus of Fig. 1, partly in vertical section.

Fig. 4 is an elevational view of a can hook.

45 Fig. 5 is a plan view of the same.

Fig. 6 is a side elevational view of the same.

Referring to the drawings, F is a freezing tank beneath a traveling crane or carriage C 50 comprising the beams or girders 1, 1, having the end frames 2 in which are journeled the wheels or rollers 3 traveling upon the rails 4 carried by the beams 5 suitably supported upon walls or columns in well known manner.

Supported upon the crane is the electric

motor M¹ which moves the crane longitudinally on the rails 4 in well known manner through suitable gearing, comprising the motor driven worm 6 meshing with and driving a gear 7 secured upon the shaft of one of the wheels 3.

Carried by the crane is a transversely extending tank or reservoir A divided into compartments by the partitions 8 whereby there is formed within the tank A a plurality of smaller tanks each having a capacity suitable for filling an ice can B to suitable depth. One row of cans B is shown in the freezing tank F, in which may be any 70 suitable number of rows of cans.

Disposed above the crane is the water supply pipe 9, controlled by valve 10, and having a plurality of discharge outlets 11, whereby upon opening the valve 10 water is 75 delivered into the tank A to a depth equal to the height of the partitions 8. From each compartment between partitions 8 in the tank A is an outlet 12, Fig. 3, communicating through a valve 13 with a hose 14, which is of sufficient length to reach the can B for filling the same. For the sake of clearness, only one such outlet and hose are shown. Preferably the operating handles of all the valves 13 are simultaneously operated by 80 any suitable means.

In the freezing tank F containing brine solution f are a plurality of banks of freezing pipes 15 disposed upon suitable racks 15^a, between which racks the cans B are disposed. Through the pipes 15 is circulated any suitable refrigerating medium for lowering the temperature within the tank F to such point that the water within the cans B freezes. Upon each rack is disposed a timber or member 16, and upon these members 16 rest the removable can covers or floor boards 17.

Carried by the crane is the electric motor M² which through suitable gearing drives 100 the shaft 18, upon which is secured the drum 19 upon which is wrapped the endless wire rope or chain 20, which passes over the sheaves 21 and 22, of which the sheaves 21 are journaled in the vertically movable 105 beam or girder 23 comprising the channel irons 24, Fig. 2, between which the sheaves 21 are disposed. The sheaves 22 are secured upon shafts 25 journaled upon the crane beams 1, 1.

Supported upon the girder 23 by members 26 is the transversely extending hori-

zontal rod 27 upon which are hooked the can hooks 28.

These hooks may be formed of spring steel rods formed to the structure illustrated in Figs. 4 to 6 inclusive. Each hook is made of a single piece of rod having the vertically extending members 29 having the outwardly extending ends 30. At its upper end each member 29 is bent over to form a hook 31 which continues in the return bend 32 lying side by side with the portion 31; the return bends are joined by the transversely extending horizontal member 33.

The outwardly extending ends 30 are adapted to be sprung into holes 34 in opposite sides of a can B, while the hook portions 31, 32 hook upon the aforementioned rod 27, whereby a can may be suspended upon the aforementioned hoisting mechanism driven by the hoisting motor M².

Carried by the crane is a third electric motor M³ driving the worm 35, Fig. 3, meshing with and driving the gear 36, which in turn drives the pinion 37, which drives the gear 38 secured upon the shaft 39 upon which are secured a plurality of chain wheels or pulleys 40. Engaging each wheel 40 is a chain 41, which passes over the idler chain wheel 42. One end of each of the chains 41 is attached at 43 to one edge or side of the dumping board or frame 44, to whose other edge or side at 45 is attached the other end of the chain 41. At one edge of the board 44 is the rail or rest 46 extending longitudinally of the frame 44, and at its other edge is a similar ledge or rail 47, preferably of less height than the member 46.

Extending parallel with the freezing tank F is a dip tank or thawing tank D containing warm water. Preferably adjacent the dip tank is the inclined chute or ice slide E adjacent the platform 48.

The operation is as follows:

When the water within the cans B in tank F has been frozen, the covers 17 are removed, the can hooks inserted in the holes 34 and the motor M² set into operation to actuate the hoisting mechanism, whereby the rod 27 upon which the can hooks engage is raised, lifting the cans filled with ice out of the freezing tank F to a position similar to that indicated in Fig. 2. Thereupon the motor M¹ is energized and the crane moved longitudinally of the rails 4 until the cans B are suspended directly above the dip tank D, whereupon they are lowered into the same and the warm water therein contacting the outside of each of the cans thaws the ice loose from the can. The cans are then again hoisted by the motor M² to a position similar to that indicated in Fig. 2. Thereupon the motor M³ is energized, moving the chain 41 and the interconnected dump board 44 to position such that the bottom of each can rests against the member 46 on the board

44; the movement of the chain is continued, in the direction of the arrow, Fig. 3, until the cans are lying upon their sides upon the board 44, as indicated in Fig. 3, the bottom of each can being slightly elevated, whereupon the ice slides out from the can and down the ice slide E to the receiving platform 48, from which it is then removed. Thereupon the motor M³ is reversed and the cans and board 44 brought back to a position such as indicated in Fig. 2, whereupon the motor M¹ is energized and the crane moves the cans to position above the freezing tank. The cans are then lowered and guided into the spaces between the racks for the pipes 15. The cans will, however, float because the tank F contains brine solution; thereupon the hose 14 are lowered, one inserted in each can and the valves 13 operated, whereupon water from the compartments in the tank A flows into the cans and they gradually settle, finally taking the position indicated in Fig. 1. Thereupon the can hooks are removed and the covers 17 replaced.

The crane may then be moved to position directly beneath the pipe 9, whereupon the valve 10 is opened and the compartments in the tank A again filled.

What I claim is:

1. Ice making apparatus comprising the combination with an ice can, of means for freezing water in said can, means for suspending said can, a dump board, and means for actuating the dump board to receive the can thereon.

2. Ice making apparatus comprising the combination with an ice can, of means for freezing water in said can, means for suspending said can, a flexibly suspended dump board, and means for actuating said dump board to engage said can and move the same to inclined position.

3. Ice making apparatus comprising the combination with an ice can, of means for freezing water in said can, means for suspending said can, a dump board, projections on opposite sides thereof between which said can is received, and means for moving said dump board to engage said can, and move the same to position for removal of ice therefrom.

4. Ice making apparatus comprising the combination with an ice can, of means for freezing water in said can, means for suspending said can, a flexibly suspended dump board for receiving said can with its side in engagement with said board, and means for actuating said board to engage said can and move the same to position in which the side of said can is inclined.

5. Ice making apparatus comprising the combination with an ice can, of means for freezing water in said can, a dump board normally in vertical position for receiving said can with its side against said board,

- 2 chain connected to opposite sides of said board, and means for actuating said chain to tilt said board and can. 70
6. Ice making apparatus comprising the combination with an ice can, of means for freezing water therein, means for hoisting said can, a dump board on which said can is received, and motor actuated mechanism for moving said dump board into operative relation with said can and for tilting said board and can. 75
7. Ice making apparatus comprising the combination with an ice can, of means for freezing water therein, a traveling carriage, means on said carriage for hoisting said can, a dump board carried by said carriage and adapted to receive said can, and means on said carriage for tilting said dump board and can. 80
- 10 8. Ice making apparatus comprising the combination with an ice can, of means for freezing water therein, a traveling carriage, means on said carriage for hoisting said can, a dump board adapted to receive said can, means flexibly suspending said board from said carriage, and means on said carriage for actuating said dump board and can through said flexible suspension. 85
- 15 9. Ice making apparatus comprising the combination with an ice can, of means for freezing water therein, a carriage, means on said carriage for hoisting said can, a dump board adapted to receive said can, a chain connected to said dump board and supporting the same on said carriage, and means on said carriage for actuating said chain to tilt said board and can. 90
- 20 10. The combination with a freezing tank, of a can therein, a traveling carriage, means on said carriage for hoisting said can from said tank, a dip tank into which said can may be lowered and removed therefrom by said hoisting means, a dump board adapted to receive said can, and means on said carriage for moving said dump board into operative relation with said can and for tilting said board and said can. 95
- 25 11. The combination with a freezing tank, of a can therein, a traveling carriage, a water tank on said carriage, means for delivering water from said tank into said can, and means on said carriage for raising and lowering said can from and into said freezing tank. 100
- 30 12. Apparatus for making can ice comprising a series of cans, means for freezing water therein, a traveling carriage, means on said carriage for hoisting said cans, dumping structure carried by said carriage and adapted to receive said cans, and means for tilting said dumping structure and the cans thereon to position to cause ice to be delivered from said cans. 110
- 35 13. Apparatus for making can ice comprising a series of cans, means for freezing water therein, a traveling carriage, means on said carriage for hoisting said cans, a dump board carried by said carriage, and means on said carriage for tilting said dump board and said cans thereon. 115
- 40 14. Apparatus for making can ice comprising a series of cans, means for freezing water therein, a traveling carriage, means on said carriage for hoisting said cans, a dump board adapted to receive said cans, means flexibly suspending said board from said carriage, and means on said carriage for actuating said dump board and cans through said flexible suspension. 120
- 45 15. Apparatus for making can ice comprising a freezing tank, a series of cans therein, a traveling carriage, a water tank thereon containing water to be delivered into said cans, means on said carriage for hoisting said cans from said freezing tank, means for thawing the ice loose from said cans, dumping structure adapted to receive said cans, and means for tilting said dumping structure and said cans to position to discharge ice from said cans. 125
- 50 16. Apparatus for making can ice comprising a freezing tank, a series of cans therein, a traveling carriage, a water tank thereon containing water to be delivered into said cans, means on said carriage for hoisting said cans from said freezing tank, means for thawing the ice loose from said cans, dumping structure carried by said carriage and adapted to receive said cans, and means on said carriage for tilting said structure and cans to position to discharge ice from said cans. 130
- 55 17. Apparatus for making can ice comprising a freezing tank, a series of cans therein, a traveling carriage, a water tank thereon containing water to be delivered into said cans, means on said carriage for hoisting said cans from said freezing tank, means for thawing the ice loose from said cans, a dumping board adapted to receive said cans, means for flexibly suspending said board from said carriage, and means on said carriage for actuating said dump board and cans through said flexible suspension to position to discharge ice from said cans. 135
- 60 18. Apparatus for making can ice comprising a freezing tank, a series of cans therein, a traveling carriage, a container on said carriage for each of said cans adapted to contain water to be delivered into said cans, means on said carriage for hoisting said cans from said tank, means for thawing the ice loose from said cans, dumping structure carried by said carriage and adapted to receive said cans, and means for tilting said dumping structure and said cans to position to deliver ice from said cans. 140
- 65 19. Apparatus for making can ice comprising a freezing tank, a series of cans. 145

therein, a traveling carriage, means thereon for hoisting said cans from said tank, dumping structure flexibly suspended from said carriage for receiving said cans with 5 their sides in engagement with said structure, and means for moving said dumping structure and said cans to position for delivering ice from said cans.

20. Apparatus for making can ice comprising a freezing tank, a dip tank, a receiving platform, a traveling carriage, means thereon for hoisting said cans from and lowering them into said tanks, dumping structure carried by said carriage and adapted to receive said cans, and means for tilting said structure with the cans thereon to position to deliver ice to said receiving platform.

21. Apparatus for making can ice comprising a freezing tank, a series of cans 15 therein, a traveling carriage, a water tank on said carriage, said tank having compart-

ments for each of said cans and means for delivering water from each compartment to its corresponding can, and means on said carriage for raising and lowering said cans 25 from and into said freezing tank.

22. Apparatus for making can ice comprising a freezing tank, a can therein, a dip tank, a receiving platform, a traveling carriage, means on said carriage for raising and 30 lowering said can from and into said freezing tank and said dip tank, a dump board carried by said carriage, said dump board normally in vertical position adjacent said can in raised position, and means for tilting said dump board to engage said can and tilt the same to position for the removal of ice.

In testimony whereof I have hereunto affixed my signature this 4th day of March, 40 1918.

GEORGE L. REUSCHLINE.
